MARINE VESSEL

John Napoli, Monterey, Calif.

Application July 8, 1940, Serial No. 344,323

2 Claims. (Cl. 114—56)

This invention relates to improvements in boats, and more particularly to an improved marine vessel having a hull which is formed with a novel sub-structure.

An object of my invention is to provide an improved boat construction, capable of being embodied in either large or small marine vessels, having a hull and an integrally formed sub-structure which is adapted to give greater stability to the vessel and to improve its operation under varying conditions.

Another object of my invention is to provide an improved hull construction of the kind characterized having a novel sub-structure and which is so designed and constructed as to materially reduce the usual rolling and dipping movement of the vessel, and at the same time cause its speed through the water to be increased without the application of additional power.

Other and further objects of my invention will be pointed out hereinafter, indicated in the appended claims, or will be obvious to one skilled in the art upon an understanding of the present disclosure. For the purpose of this application, I have elected to show herein certain forms and details of a marine vessel representative of my invention; it is to be understood, however, that the embodiments of my invention herein shown and described are for purposes of illustration only, and that therefore they are not to be regarded as exhaustive of the variations of the invention, nor are they to be given interpretations such as might have the effect of limiting the claims short of the true and most comprehensive scope of the invention in the art.

In the accompanying drawing:

Fig. 1 is a side view of a marine vessel embodying the principles of my invention;

Fig. 2 is a front view of my invention; and

Fig. 3 is a sectional view taken on the line 3—3 of Fig. 1, showing the internal supporting structure of the vessel removed.

In the drawing I have illustrated a marine vessel or boat of the kind adapted to carry passengers or freight, and for the sake of simplicity and clarity I have purposely eliminated the usual super-structure and the internal operating and the controlling mechanism. The numeral 1 designates the boat's hull which includes the bow 2 and the stern 3. A deck 4 enclosing the interior of the boat is preferably somewhat convex, but not necessarily so. The boat is preferably propelled through the water by two pairs of propellers, 5 and 6, the former being positioned at opposite sides of the bow and the latter at oppo-

site sides of the stern. A rudder 7 is positioned in the usual manner at the stern of the boat. The propellers and the rudder are operatively connected to and are actuated in the customary manner by suitable mechanism provided within the hull 1.

The upper part of the hull, directly beneath the juncture of the deck 4 therewith, is preferably curved outwardly slightly as at 8, thereby providing a slightly concave surface which tends to deflect the water striking the same in an outward direction so it does not wash over the said deck.

The lower part of the hull 1 curves inwardly as at 9 and is integrally joined as at 10 to a sub-structure 11. The sub-structure extends lengthwise beneath the hull and its forward end 12 is pointed so as to cut through the water without offering an undue amount of resistance. From 10 the sub-structure 11 curves outwardly at 13 to 14, and thence it curves inwardly at 15 and is joined to a longitudinally and centrally disposed member or keel 16.

The areas 9, 10, and 13 preferably assume a gradual curve which is sufficiently streamlined to reduce the water resistance materially. At 17, where the forward end of the bow joins the forward end of the sub-structure, there is provided a streamlined surface which blends into and is complementary to the streamlined surfaces 9, 10 and 13 located directly to the rear thereof. The rear end of the sub-structure 11 is positioned beneath the stern 3, and the surfaces located therebetween are also streamlined.

The width of the sub-structure 11 at its central part is preferably a little wider than the extreme width of a corresponding section of the hull. The sub-structure 11, being positioned well beneath the surface of the water where it is not materially influenced by surface waves and surface currents, constitutes a broad base for maintaining the hull in a normal position. The surface waves directed in the normal way against the hull 1 will not cause the latter to roll or dip to the extent it would if the sub-structure 11 were not joined thereto. In view of the comparative stability of a vessel embodying my invention during its normal operation, and since the movements thereof other than straight ahead are substantially reduced, its traveling speed is somewhat increased. The straight forward movement of the vessel is also more satisfactorily maintained since the contra currents at the surface of the water do not normally cause its deviation from a plotted course. With the

increased stability of the vessel there is an accompanying decrease in traveling discomfiture, for with a substantial reduction in the roll and dip of the vessel there is less chance of passengers becoming seasick. The sub-structure 11 may enclose a cargo carrying compartment if it is so desired, or it may be constructed without a useful or other space being provided therein.

While I have shown and described the sub-structure 11 as having a definite construction and shape, it is to be understood that other modifications of my invention are entirely possible.

Having described my invention, what I claim is:

1. A hull comprising an integral structure having an upper part normally disposed substantially above the load water line and a lower normally submerged part extending longitudinally beneath the upper part, the said upper and lower parts of the hull being of substantially equal depths, the said lower part having outwardly curved upper sides joined to the sides of the upper part of the hull, and lower curved sides joined to outer edges of the upper sides of the lower part of the hull, the said lower curved sides being joined to a keel and forming a longitudinally disposed substantially V-shaped structure extending above the keel, the upper curved sides and lower curved sides forming a substantially sharp outwardly projecting lateral edge substan-

tially wider than the hull's upper part, the said lower part having a pointed forward end, and the said lower part of the hull having a cargo carrying space joining the space above in the upper part of the hull.

2. A hull comprising an integral structure having an upper part normally disposed substantially above the load water line, and a lower submerged part extending longitudinally beneath the upper part, the said upper and lower parts of the hull being of substantially the same depths, the said lower part having outwardly curved upper sides forming downwardly and outwardly disposed extensions of the sides of the hull's upper part, the said lower part also having concave curved lower sides disposed at an acute angle with respect to each other and joined at their outer edges to the outer edges of the upper curved sides and at their inner lower edges to a longitudinally disposed depending keel, the said lower part of the hull having substantially sharp lateral edges which are disposed in a substantially horizontal plane and which converge at their forward ends to form a pointed forward end for reducing the resistance of the lower part of the hull when operating through the water, and the said lower part of the hull having a cargo carrying space joining the space above in the upper part of the hull.

JOHN NAPOLI.
